(57) **CLAIM**

The ornamental design for a pet litter scoop, as shown and described.

DESCRIPTION

FIG. 1 is a front perspective view of the pet litter scoop, showing the new design;

FIG. 2 is a top plan view thereof;

FIG. 3 is a bottom plan view thereof;

FIG. 4 is a side elevational view thereof;

FIG. 5 is another side elevational view thereof;

FIG. 6 is a rear elevational view thereof; and,

FIG. 7 is front elevational view thereof.

The broken lines showing various elements of the pet litter scoop are included for the purpose of illustrating environmental structure and form no part of the claimed design.

1 Claim, 6 Drawing Sheets(56)
